UNITED STATES PATENT OFFICE

2,625,106

COMPOSITE PUMP FOR PRIME MOVER
OIL SYSTEMSHerbert N. Hoffman, Wakefield, Mass., assignor
to General Electric Company, a corporation of
New York

Application September 12, 1950, Serial No. 184,481

2 Claims. (Cl. 103—4)

1

This invention relates to a special composite pump for furnishing hydraulic power and lubricating liquid in a prime mover, specifically a combination positive displacement and centrifugal pump unit for supplying lubricating oil to the bearings, hydraulic fluid to the governing system, and a speed-pressure signal for effecting the governing function in a steam turbine.

The pump described herein is specifically intended to be used in a hydraulic turbine governing system as described in the copending application of Stephen Jacobs, Serial No. 22,785, filed April 23, 1948, now Patent No. 2,534,974 and assigned to the same assignee as the present application. That system incorporated a so-called "turbine-type" centrifugal pump further details of which are disclosed in the copending application of Stephen Jacobs, Serial No. 116,255, filed September 17, 1949, and my copending application Serial No. 129,490, filed November 25, 1949, now abandoned.

Experience with the turbine-type pumps of these copending applications has shown that in some turbines it is not feasible to obtain all the hydraulic operating liquid, lubricating oil, and other pressure liquid needed in the operation of the prime mover and its governing system from a single turbine-type impeller. In certain turbines, the quantity of hydraulic power and lubricating oil required exceeds that which can be obtained from a single impeller of the turbine type; therefore, a principal purpose of the present invention is to provide a composite pump having a positive displacement pump element for supplying the lubricating and hydraulic power liquid, while a comparatively small turbine-type centrifugal pump element serves only to supply the speed-pressure signal for controlling the governing system.

Another object is to provide a composite pump of the type described in which the turbine-type impeller is closely related to the positive displacement rotors so that the whole occupies little more space than a conventional positive displacement pump alone.

A still further object is to provide a composite positive displacement-turbine type pump in which the centrifugal rotor receives its operating liquid from the positive displacement pump, with special means for insuring that the pressure signal generated by the centrifugal rotor will be truly proportional to speed and unaffected by the discharge pressure of the positive displacement pump, having also passages arranged to effect a limited circulation of oil to prevent overheating

of the centrifugal rotor and to insure that it will be "self-priming," so that the pump can be mounted above the level of the liquid in the system with which it is connected.

In general, these objects are attained by arranging the small centrifugal turbine-type rotor on a shaft common to one of the positive displacement pump rotors and directly below, so that liquid leaking downwardly from the positive displacement pump provides the supply of liquid needed by the centrifugal turbine-type pump. A reservoir open to the atmosphere is disposed above the centrifugal pump rotor and communicates with the inlet side thereof so that any excess liquid supplied from the positive displacement pump passes to the reservoir and overflows, with the result that the static head at the inlet to the centrifugal pump rotor is maintained exactly constant and the thermal circulation between the centrifugal pump passages and the reservoir serves to cool the centrifugal rotor.

Other objects and advantages will be apparent from the following description, taken in connection with the accompanying drawings in which Fig. 1 is a top view, partly in section, of the composite pump unit; Fig. 2 is a sectional assembly view taken on the irregular plane 2—2 in Fig. 1; Fig. 3 is an enlarged elevation view of the centrifugal turbine-type impeller; Fig. 4 is a bottom view in elevation of one of the disk members forming the centrifugal impeller housing, taken in the direction 4—4 in Fig. 2; Fig. 5 is a top view in elevation of the disk member separating the centrifugal rotor housing from the variable displacement rotor housing, taken in the direction 5—5 in Fig. 2; and Fig. 6 is a partial sectional view of the complete assembly taken on the plane 6—6 in Fig. 1.

Referring now more particularly to Fig. 2, the assembly comprises a main housing member 1, an intermediate disk or plate member 2 which, in effect, forms the bottom of the main housing 1, and a pair of disk members 3, 4 which form the housing for the centrifugal element. As will be seen by comparison of Figs. 1 and 2, the main housing casting 1 is generally cylindrical in shape and has an eccentrically located upwardly extending portion 1a defining a multiple-lobed recess 5, which houses the two intermeshing gears 6, 7 constituting the positive displacement pumping units. As may be seen in Fig. 2, the pump gear 6 has projecting shaft end portions 6a, 6b, shaft 6a projecting upwardly through an opening in casting 1a and carrying a spiral gear 8 adapted to engage a mating gear on the turbine shaft so

as to be driven at a fixed speed ratio relative to turbine shaft speed. Gear 8 may, of course, be locked on a shoulder formed on shaft 6a by means of a lock nut 8a or other suitable means. The complementary gear 7 also has projecting shaft end portions 7a, 7b. As will be seen in Fig. 2, the lower shaft end portions 6b, 7b are supported in holes in the bottom plate 2 forming journal bearings. Shaft 7b has a reduced diameter end portion 7c which serves to support and drive the centrifugal turbine-type impeller 9, as described more particularly hereinafter.

Referring again to Fig. 1, it will be seen that the two pump gears 6, 7 occupy diametrically opposed lobes of the recess 5, the other lobes forming the inlet and discharge chambers 5a, 5b, respectively, for the positive displacement pump. An inlet conduit 10 is cast integral with the housing 1a and communicates with the inlet chamber 5a. Similarly, a discharge conduit 11 communicates with the discharge chamber 5b.

The offset portion of housing 1 at the side of the housing portion 1a defines a liquid reservoir indicated generally at 12 in Figs. 1 and 2. This reservoir is bounded externally by the semi-cylindrical wall 13 and consists of three distinct portions. The first is the comparatively shallow portion indicated at 12a in Figs. 1 and 6. The second is the deeper portion identified at 12b in Figs. 1 and 2. The third portion constitutes a comparatively small sump identified 12c in Figs. 1 and 2.

A top elevation view of the intermediate plate 2 is shown in Fig. 5, and a cross section of this plate is seen in Fig. 2. From these views it will be apparent that plate 2 is secured to the main housing portion 1 by a plurality of circumferentially spaced threaded fastenings 14 disposed in counterbored holes 15 in plate 2. Plate 2 is also provided with an axially extending hole 16 and a smaller hole 17, located at substantially the same radius as hole 16, the purpose of which will appear hereinafter. The centrifugal pump housing plates 3, 4 are secured to the pump body 1 by a plurality of circumferentially spaced threaded fastenings 18 disposed in holes 18a in the plates 3 and 4 (Fig. 4) and corresponding holes 18b in the intermediate plate 2. Plate 2 is accurately located relative to the pump housing 1 by a pair of diametrically spaced dowel pins, one of which is indicated in dotted lines at 19 in Fig. 2, which pins project through holes 19a in intermediate plate 2 (Fig. 5).

In order to locate the centrifugal pump housing plate 3 accurately relative to the intermediate plate 2 the latter may be formed with an annular land 2a forming a rabbet fit with the central recess 20 of plate 3, as may be seen in Fig. 2. Similarly, in order to locate accurately the bottom plate 4 relative to the upper plate 3, plate 4 may be provided with a land 4a engaging a rabbet in the adjacent surface of plate 3.

A bottom view of the upper centrifugal pump housing plate 3 is shown in Fig. 4. By comparison of Figs. 2 and 4, it will be apparent that this plate defines a central recess 20 which cooperates with a recess of the same diameter 21 in the lower plate 4 to form the central portion of the centrifugal impeller chamber. The annular land 22 which surrounds recess 20 is interrupted by a groove 23 which forms the inlet to the centrifugal pumping passage 24 shown in plan view in Fig. 4 and in section in Fig. 2. A hole 16b in plate 3 communicates between the aforementioned hole 16 in the intermediate plate

2 and a third hole portion 16c in the main housing 1. It will be apparent from Figs. 1 and 2 that the cooperating holes 16, 16b, 16c constitute a vertical passage or "standpipe" communicating with the sump 12c of the reservoir 12.

As will be seen in Fig. 4, the substantially annular groove 24 communicates with an enlarged inlet portion 24a and a smaller enlarged terminal portion 24b, the latter communicating with a discharge port 17a. As may be seen in Fig. 6, port 17a communicates with axial hole 17 in intermediate plate 2, which in turn communicates with a drilled passage in main housing portion 1, including an axial hole 17b, a radially extending hole 17c, which continues through an integrally cast extension 1b of the main housing 1. The plan view of this housing portion 1b may be seen in Fig. 1. It will be apparent from Figs. 1 and 6 that the drilled hole 17c is closed by a plug 26 and communicates with another drilled hole 17d which opens through the flange 10a associated with the main inlet conduit 10.

It will be understood from Fig. 2 that the bottom centrifugal pump housing plate 4 is provided with complementary recesses corresponding to the above-described items identified at 23, 24a, 24, 24b in connection with upper plate 3. To eliminate unnecessary duplication of reference numerals, the whole inlet chamber will be referred to as 24a, the annular pumping passage as 24, and the discharge chamber as 24b.

The centrifugal turbine-type impeller is shown in plan view in Fig. 3 and in section in Fig. 2. As will be apparent from Fig. 3, this consists of a disk having an enlarged hub portion 9a with a bore 25 including axial keyways 25a adapted to engage a key 26a, as illustrated in Fig. 2. It is to be understood that the impeller hub portion 9a does not fit tightly on the shaft extension 7c but forms a sufficiently free fit therewith, and with the keys 26a, that the impeller is free to shift very slightly relative to the shaft so as to properly center itself between the annular land 22 of the upper housing plate 3 and the similar cooperating land 27 of the lower plate 4. It will be understood by those familiar with the art pertaining to this type of pump that these lands form small clearance spaces with the sides of the impeller web portion 9b, as indicated at 22a, 27a, respectively, in Fig. 2. The hydraulic forces resulting from the liquid in these clearance spaces will tend to center the impeller axially on the shaft extension 7c so that these clearance spaces are equal. These clearances are shown somewhat exaggerated in size in the drawing, being actually on the order of .003 inch in a pump with a 2 1/2 inch diameter impeller.

The blades of the impeller 9 are formed simply by cutting axial slots in the rim of the web portion 9b so as to form the radially projecting blades 9c. It will also be seen that the hub portion 9a of the impeller is provided with two diametrically opposed pressure balancing holes 28 which communicate liquid from the top side of the impeller to the bottom side thereof so that there will be no pressure differential tending to move the impeller axially on its shaft.

To provide lubrication for the gear rotor shafts 6a, 7a, the journal bearing bores in the upper portion of housing 1 are provided with axially extending grooves shown at 6c, 7e, respectively, between which communicates a transverse groove 29. This groove 29 insures that oil will be supplied freely to both axial grooves 6c, 7e. These

axial grooves do not extend all the way through the housing 1, but are provided with a small land or dam, shown at 6e, 17 at the exterior side of the housing to prevent excessive loss of lubricating oil from the grooves.

For lubricating the shaft extensions 6b, 7b, the intermediate plate 2 is likewise provided with axially extending grooves 6d, 7d connected by a transverse groove 30. Unlike the first mentioned axial grooves 6c, 1c, these do extend all the way downwardly through the thickness of intermediate plate 2 so as to provide a definite leakage path from the positive displacement pump into the annular recess 20, which leakage constitutes the supply of liquid to the centrifugal turbine-type impeller 9. To facilitate discharge of oil from groove 6d into recess 20, a groove 30a, disposed parallel to groove 30, may be formed in the lower surface of plate 2.

Having now described all the passages constituting the various paths for the liquid through the pump, the operation will be seen to be as follows: Since the positive displacement pump 6, 7 is capable of priming itself, the inlet conduit 10 may communicate with a source of oil which is either above or below the level of the pump. Ordinarily, when used in a steam turbine governing system, the entire pump assembly will be supported within an enclosing sump or tank adjacent the turbine shaft, as disclosed in the above-mentioned application of Stephen Jacobs, Serial No. 22,785. This enclosing tank or sump may constitute the liquid reservoir for the hydraulic system, or a separate external tank may be provided from which oil is supplied to the conduit 10. Rotation of the gear pump impellers 6, 7 (gear 6 rotating counterclockwise as indicated by the arrow in Fig. 1) draws liquid from the inlet chamber 5a and delivers it under pressure to the discharge chamber 5b. The main discharge from the pump is through the conduit 11, which supplies the bearing lubrication system, hydraulic motor for positioning the turbine inlet valve, and other devices about the turbine which require oil under pressure.

The sole function of the centrifugal turbine-type impeller 9 is to provide a liquid signal pressure bearing a preselected relation to turbine shaft speed. This pressure is communicated to a suitable pressure responsive element (not shown), such as a closed flexible bellows associated with the turbine governor. As will be appreciated by those familiar with turbine governing systems of this type, the only flow required from the centrifugal pressure signal generator is that small amount required to make up for any small leaks which may occur in the pressure sensing device of the turbine governor. For all practical purposes it may be assumed that there is zero flow from the centrifugal pump element. In other words, the impeller 9 is a "static pressure generator," rather than a "flow supplier."

It will be understood from the above description of the structure that rotation of the impeller 9 causes liquid to be drawn in from the central recess 20, which is kept full of oil by the above-described leakage through the lubricating grooves 6d, 7d. The dimensions of these oil grooves 6d, 7d, etc., are so selected that the rate of oil supply to the recess 20 is at all times greater than the comparatively small flow discharged from the centrifugal pump through outlet 17. It will be understood that the discharge pressure of the positive displacement pump will insure that there will be a positive flow through the oil grooves 6d, 7d.

7d into the recess 20. Oil from inlet chamber 20 communicates by way of the inlet groove 23 in the upper plate 3, and the corresponding groove in the lower plate 4, with the pump inlet chamber 24a, whence the centrifugal action of the impeller blades 9c causes the fluid to be carried around through the pumping passage 24 to the discharge port 11a. The pressure thus generated at port 11a causes oil to flow through the related passages 17, 17b, 17c, 17d (Fig. 6). The pressure signal from conduit 17d is communicated to the turbine governor by a suitable conduit (not shown).

Of course, this flow will take place principally when the system is started up, and will continue only until all the passages are full, after which the only flow taken from the centrifugal rotor will be that required to make up for leakage. Thus in normal operation the fluid in the discharge passages communicating with the centrifugal rotor is substantially stagnant, which means that hydraulic friction and other energy losses in the centrifugal pump passages generate a substantial amount of heat, which must be dissipated in order to prevent excessive changes in viscosity of the operating liquid. This heat dissipation is one of the several functions performed by the vertical "standpipe" comprising the cooperating passages 16, 16b, 16c.

The pressure of the oil supplied to the central recess 20 and thence to the inlet chamber 24a of the turbine pump is sufficient to cause oil to circulate upwardly through the standpipe, fill the reservoir 12, and overflow the circumferential edge 13 bounding the reservoir. Thus the reservoir is always kept full of liquid, with the further result that the static head of the liquid at the inlet 24a to the pumping passage 24 is maintained exactly constant. This is important if the discharge pressure generated by the centrifugal rotor is to be a true function of turbine shaft speed. It will be apparent that with this arrangement any variations in discharge pressure of the positive displacement pump 6, 7 have no effect on the discharge pressure of the centrifugal element, since variations in positive displacement pump pressure merely change the rate at which excess oil overflows from the reservoir 12.

The above-described circulation of excess oil past the impeller hub portion 9a and out through the standpipe serves to cool the impeller and thus limit the temperature rise produced by the churning of the oil in the centrifugal pump.

Still another function of the reservoir 12 and standpipe 16, etc., lies in the fact that when the machine stops, the reservoir will keep the positive displacement and centrifugal pump chambers and related passages filled with oil so that, when operation begins again, the centrifugal pump will be completely flooded and thus is "self-priming." This is an important feature, since the rate of flow through the centrifugal pump element is so small that without this self-priming feature the pump may not be able to clear itself of air when starting, with the result that discharge pressure would not accurately represent pump speed.

Thus it will be seen that the invention provides a simple and extremely compact composite pump, the positive displacement portion of which may be made of any desired capacity to supply the lubricating and governing oil requirements of a turbine, while the pressure signal required for the governing system is supplied by a comparatively small centrifugal impeller, the pressure sig-

nal being accurately representative of the shaft speed by reason of the fact that the standpipe arrangement keeps the inlet pressure to the centrifugal pump element constant, while at the same time performing the above-described cooling and self-priming functions.

While only one specific form of the invention has been described in detail, it will be obvious to those skilled in the art that many changes may be made. As suggested, the positive displacement pump may be made of greater capacity simply by making the gear impellers 6, 7 of greater axial length, without changing the construction or characteristics of the centrifugal pressure generating element. Likewise centrifugal rotors of slightly different construction may be employed, for instance those shown in my above-mentioned application Serial No. 129,490 or the application of Stephen Jacobs, Serial No. 22,785. Also, other types of positive displacement pump may be employed. It will also be obvious that the arrangement of the casing elements and the passages therein may be greatly modified, as long as they perform the same functions in substantially the manner described above. For instance, the grooves 6d, 7d may be omitted and the normal leakage from the bearings relied upon to supply the centrifugal rotor. It is, of course, intended to cover by the appended claims all such modifications and changes as fall within the true spirit and scope of the invention.

What I claim as new and desire to secure by Letters Patent of the United States is:

1. In a composite positive displacement-centrifugal pump, the combination of a positive displacement pump having at least one driven rotor member, first housing walls enclosing the rotor and defining inlet and discharge chambers associated with the rotor and journal means supporting the rotor, second centrifugal pump housing walls immediately adjacent the positive displacement pump and defining a central circular recess surrounded by an annular turbine-type pumping passage extending less than 360 degrees circumferentially, a turbine-type centrifugal pump rotor with a central hub portion disposed in said recess and a bladed rim portion projecting into said annular pumping passage, the positive displacement pump rotor having a shaft extension supporting and driving the centrifugal rotor, said first and second housing walls defining passages adapted to supply liquid under pressure from the positive displacement pump to the central recess in the centrifugal pump housing, the centrifugal pump housing walls defining an inlet passage communicating between the central recess and the inlet end of the annular pumping passage, said second housing walls also defining a discharge passage communicating with the end of the pumping passage remote from said inlet, said first housing walls also forming a reservoir disposed above the level of the centrifugal pump and open to the atmo-

sphere and having a passage connecting the lowermost portion thereof with the inlet end of the annular pumping passage, whereby when the rate of discharge from the centrifugal pump rotor is less than the rate of supply of liquid from the positive displacement pump to the centrifugal pump, the excess liquid fills the reservoir and overflows so as to maintain a constant static head at the inlet end of the centrifugal pumping passage and the circulation of excess liquid past the centrifugal rotor effects cooling thereof.

2. In a composite pump, the combination of a positive displacement pump having at least one driven rotor member, first housing walls enclosing the rotor and defining inlet and discharge chambers associated with the rotor and journal means supporting the rotor, second housing walls adjacent said first walls and defining a central circular recess surrounded by an annular turbine-type pumping passage extending less than 360° around the central recess, a turbine-type centrifugal pump rotor with a central hub portion disposed in said recess and a bladed rim portion projecting into the annular pumping passage, the positive displacement pump rotor having a shaft extension supporting and driving the centrifugal rotor, said first and second housing walls defining passages for supplying liquid under pressure from the positive displacement pump to the central recess in the centrifugal pump, said second housing walls defining an inlet passage communicating between the central recess and the inlet end of the annular pumping passage, said second housing walls defining also a discharge port at the end of the annular pumping passage remote from said inlet the first housing walls forming a reservoir above the level of the centrifugal pump and open to the atmosphere, said first and second housing walls having passages cooperating to define a standpipe communicating between said reservoir and the inlet end of the annular pumping passage, whereby excess liquid supplied from the positive displacement pump to the centrifugal pump fills the reservoir and overflows so as to maintain a constant static head at the inlet end of the annular centrifugal pumping passage while the circulation of excess liquid past the centrifugal rotor effects cooling thereof.
